CLAIM

The ornamental design for a attachment for a hammer head, as shown and described.

DESCRIPTION

FIG. 1 is a perspective view of an attachment for a hammer head showing my new design, with the upper portion, of a claw hammer shown in broken lines for illustrative purposes only and forming no part of the claimed design;

FIG. 2 is a left side elevational view thereof, the right side being a mirror image;

FIG. 3 is a rear elevational view thereof;

FIG. 4 is a front elevational view thereof;

FIG. 5 is a top plan view thereof; and,

FIG. 6 is a bottom plan view thereof.

FIG. 1

FIG. 2

FIG. 3

FIG. 4

FIG. 5

FIG. 6
